Primary Examiner—Cynthia E. Ramirez

(57) **CLAIM**

The ornamental design for a combined suction cup grip and lid, as shown and described.

DESCRIPTION

FIG. 1 is a perspective view of my new design;

FIG. 2 is a right elevational view thereof;

FIG. 3 is a top elevational view thereof;

FIG. 4 is a front elevational view thereof;

FIG. 5 is a bottom plan view thereof;

FIG. 6 is a left elevational view thereof;

FIG. 7 is a rear elevational view of my new design; and,

FIG. 8 is a perspective view showing the sucking cup with a protect lid.
